UNITED STATES PATENT OFFICE

2,073,378

ELECTRICAL CONNECTER

Gunner Olson, Chicago, Ill.

Application May 10, 1932, Serial No. 610,359

2 Claims. (Cl. 173—343)

My invention relates to electrical circuits, and includes among its objects and advantages the provision of an improved socket connection.

My primary object is the construction of an electric contact socket wherein the channels for the reception of plug prongs are definitely restricted to a minimum clearance, and the prongs are maintained at a substantially defined position in the channel independent of the uniform pressure of a contact element in the socket.

Another object is the construction of a socket wherein a resilient contact element is maintained in uniform pressure upon the plug prong but suffers no deterioration of its integrity by reason of a crushing effect of a plug prong.

In the accompanying drawing:

Figure 1 is a sectional view of a socket;

Figure 2 is a sectional view taken along the line 2—2 of Figure 1;

Figure 3 is a plan view of the socket of Figure 1;

In Figures 1, 2, and 3 I have illustrated a socket construction. This socket comprises a body portion 5 having slots 6 for freely receiving the usual prongs associated with standard plugs, said slots having flared openings 7. Companion recesses 8 communicate with the slots 6, said recesses extending to points 12 distant from the outlets of the slots, the bottom end of each recess being curved 9 to provide a compressional bearing for a resilient contact element 10. These contact elements 10 are substantially ogee shaped in the slots and recesses having an arcuate portion 11 arranged to frictionally engage the plug prongs when the plug and socket are coupled, and an arcuate portion 11a in contact with the curve 9 to increase the compressional contact on the prongs when inserted in the slot 6.

Referring to Figure 2 it will be noted that the recesses 8 are narrower than the slots 6, so that the walls of the slots 6 guide the inserted prongs on four sides, the portions 13 of the walls adjacent the recesses 8 forming bridge bearings for the travel thereon of contact prongs, thereby eliminating the necessity for the spring terminals 11 performing any guiding function. This construction protects the spring terminals from becoming damaged by the plug prongs, which frequently occurs when the plug is not coupled in the socket with its prongs exactly parallel with the slots in the socket. This is particularly true in socket constructions having resilient contact elements designed to compensate for wear and dimensional variations to the end that good contact may be had. In other words, the resilient contact elements are frequently bent to the extent that they lose their resiliency, thereby making it impossible to secure good electrical connection between the plug prongs and the resilient contact elements. In my construction, the resilient con-

tact elements perform no function other than to insure good electrical contact. The pressure of the arcuate portions 11 upon the inserted prongs is never more than the natural tension of the resilient contact elements.

Without further elaboration, the foregoing will so fully explain my invention that others may, by applying knowledge current at the time of application, readily adapt the same for use under various conditions of service.

I claim:

1. An electrical socket of the type described having a pair of spaced apart slots extending longitudinally through the socket, these said slots being rectangular in cross section and parallel with each other longitudinally, a dividing wall between the said slots, the said dividing wall having a recess portion either side thereof communicating from a slot inwardly toward the other slot, said recess portions extending downwardly from a position spaced apart from the entry ports of the said slots, the said recess portions being of lesser width than the slot wall which is recessed, seated in each recess a resilient member substantially ogee shaped in formation having its individual attachment to an external contact member on the socket, the width of said resilient member being slightly less than the recess portion of its channel and having a free terminal portion adapted to sink into a recess portion when pressure is brought to bear upon it, there being a portion normally extending into its communicating slot, and means in the lower portion of each recess to automatically intensify the force of the resilient member upon a plug prong.

2. In an electrical contact socket a pair of slots therethrough adapted to receive standard plug prongs, said slots being rectangular in cross section and of equal dimensions, there being a dividing wall between the said slots having on either side thereof a recess communicating with its adjacent slot each said recess being narrower than its slot wall providing a pair of opposing ledges along each of said recesses in the dividing wall, a flexible contact member of substantially ogee formation basically resting in each recess and having fixed attachment to an external portion of the socket, each of said flexible contact members having a free end portion shaped to project into the slot and sink into a recess of the dividing wall when pressure is brought to bear upon that portion of the flexible member projecting into the channel of the slot, the lower end of each recess being curved outwardly to form a fulcrum and automatically increase the pressure exerted on the plug prong when the said plug prong is pressed into the socket.
